CLAIM

I claim the ornamental design for a footbed for a shoe, as shown and described.

DESCRIPTION

FIG. 1 is a top, front, outer side isometric view of a first embodiment of a footbed for a shoe, showing my new design;

FIG. 2 is a front view of the footbed of FIG. 1.

FIG. 3 is a rear view of the footbed of FIG. 1.

FIG. 4 is an outer side view of the footbed of FIG. 1.

FIG. 5 is an inner side view of the footbed of FIG. 1.

FIG. 6 is a top view of the footbed of FIG. 1.

FIG. 7 is a bottom view of the footbed of FIG. 1.

FIG. 8 is a top, rear and inner-side isometric view of the footbed of FIG. 1.

FIG. 9 is a cross-sectional view of the footbed taken along line 9-9 of FIG. 6.

FIG. 10 is a cross-sectional view of the footbed taken along line 10-10 of FIG. 6.

FIG. 11 is a cross-sectional view of the footbed taken along line 11-11 of FIG. 6.

FIG. 12 is a cross-sectional view of the footbed taken along line 12-12 of FIG. 6.

FIG. 13 is a top, front, outer side isometric view of a second embodiment of a footbed for a shoe, showing my new design;

FIG. 14 is a front view of the footbed of FIG. 13.

FIG. 15 is a rear view of the footbed of FIG. 13.

FIG. 16 is an outer side view of the footbed of FIG. 13.

FIG. 17 is an inner side view of the footbed of FIG. 13.

FIG. 18 is a top view of the footbed of FIG. 13.

FIG. 19 is a bottom view of the footbed of FIG. 13.

FIG. 20 is a top, rear and inner-side isometric view of the footbed of FIG. 13.

FIG. 21 is a cross-sectional view of the footbed taken along line 21-21 of FIG. 18.

FIG. 22 is a cross-sectional view of the footbed taken along line 22-22 of FIG. 18.

FIG. 23 is a cross-sectional view of the footbed taken along line 23-23 of FIG. 18.

(Continued)

FIG. 24 is a cross-sectional view of the footbed taken along line 24-24 of FIG. 18.

FIG. 25 is a top, front, outer side isometric view of a third embodiment of a footbed for a shoe, showing my new design;

FIG. 26 is a front view of the footbed of FIG. 25.

FIG. 27 is a rear view of the footbed of FIG. 25.

FIG. 28 is an outer side view of the footbed of FIG. 25.

FIG. 29 is an inner side view of the footbed of FIG. 25.

FIG. 30 is a top view of the footbed of FIG. 25.

FIG. 31 is a bottom view of the footbed of FIG. 25.

FIG. 32 is a top, rear and inner-side isometric view of the footbed of FIG. 25.

FIG. 33 is a cross-sectional view of the footbed taken along line 33-33 of FIG. 30.

FIG. 34 is a cross-sectional view of the footbed taken along line 34-34 of FIG. 30.

FIG. 35 is a cross-sectional view of the footbed taken along line 35-35 of FIG. 30.

FIG. 36 is a cross-sectional view of the footbed taken along line 36-36 of FIG. 30.

FIG. 37 is a cross-sectional view of the footbed taken along line 37-37 of FIG. 30.

FIG. 38 is a cross-sectional view of the footbed taken along line 38-38 of FIG. 30.

FIG. 39 is a top, front, outer side isometric view of a fourth embodiment of a footbed for a shoe, showing my new design;

FIG. 40 is a front view of the footbed of FIG. 39.

FIG. 41 is a rear view of the footbed of FIG. 39.

FIG. 42 is an outer side view of the footbed of FIG. 39.

FIG. 43 is an inner side view of the footbed of FIG. 39.

FIG. 44 is a top view of the footbed of FIG. 39.

FIG. 45 is a bottom view of the footbed of FIG. 39.

FIG. 46 is a top, rear and inner-side isometric view of the footbed of FIG. 39.

FIG. 47 is a cross-sectional view of the footbed taken along line 47-47 of FIG. 44.

FIG. 48 is a cross-sectional view of the footbed taken along line 48-48 of FIG. 44.

FIG. 49 is a cross-sectional view of the footbed taken along line 49-49 of FIG. 44.

FIG. 50 is a cross-sectional view of the footbed taken along line 50-50 of FIG. 44.

FIG. 51 is a cross-sectional view of the footbed taken along line 51-51 of FIG. 44; and,

FIG. 52 is a cross-sectional view of the footbed taken along line 52-52 of FIG. 44.
